UNITED STATES PATENT OFFICE.

THOMAS R. MURRAY, JAMES P. MURRAY, AND EDWARD S. NEILAN, OF NEW LONDON, CONNECTICUT.

STREET-CLEANER.

1,075,489.

Specification of Letters Patent.

Patented Oct. 14, 1913.

Application filed September 11, 1912. Serial No. 719,896.

To all whom it may concern:

Be it known that we, THOMAS R. MURRAY, JAMES P. MURRAY, and EDWARD S. NEILAN, citizens of the United States, residing at New 5 London, in the county of New London and State of Connecticut, have invented new and useful Improvements in Street-Cleaners, of which the following is a specification.

This invention relates to street cleaners 13 and one of the principal objects of the invention is to provide a simple and efficient device whereby the dirt may be readily removed from the streets without causing any dust, such as is the case with sweepers.

15 A further object of the invention is to provide a vacuum operated street cleaning device in which the exhaust in the dust chamber is conveyed directly to a hood which incases the suction head so that any 20 dust escaping from the dust chamber will be again taken up by the suction head and thereby prevented from escaping.

Further objects of this invention will appear as the following specific description is 25 read in connection with the accompanying drawings which form a part of this application, and in which:—

Figure 1 is a side elevation. Fig. 2 is a rear elevation. Fig. 3 is a longitudinal section on the line 3—3 of Fig. 2. Fig. 4 is 30 a front elevation partly in section. Fig. 5 is a vertical section on the line 5—5 of Fig. 1.

Referring more particularly to the drawings, 1 represents the chassis of the ordinary motor vehicle upon which is hung the engine casing 2 having projecting therefrom the driving shaft 3 which is connected to the driving wheel 4 by means of chains 35 and sprockets 5. The front wheels are steered in the usual manner from the steering post 6 and in all other respects, the parts described are similar to an ordinary motor truck. Mounted upon the chassis is 40 a box-like body 7 which overhangs the wheels thereof and has a door 8 hinged to one side thereof so that access may be had to the dust chamber 9 for removing the dust and accumulated dirt therein. The forward portion of the body is separated from 45 the dust compartment by means of a partition 10 so as to form a suction compartment 11, as shown. This compartment has arranged therein a suitable shelf 12 upon 50 which a suction blower 13 is mounted. The

blower 13 is preferably driven by a belted connection 14 with a counter shaft 15 driven through the motor by a belt and pulley 16 and 17, the latter element being loosely mounted upon the counter shaft and being 60 connected to the shaft 15 by means of the clutch 18 controlled by a lever 19 adjacent the driver's seat 20.

The blower is provided with an exhaust 21 and with an inlet pipe 22 which extends 65 from the back of the body through the compartment 9 to a connection with the blower. The inlet pipe 22 is connected to a suction head 23 by means of an elbow 24 and a flexible joint 25 which permits the raising of 70 the suction head, as will be hereinafter described, so that the same may be thrown to an operative position and may also accommodate itself to the inaccuracies in the road surfaces.

75 The suction head and its associated parts are arranged within a hood 26 which consists of a plurality of uprights 27 connected together by rectangular frames 28 and covered with any suitable fabric 29, such as 80 canvas or the like which is attached to the separate frames in any suitable manner. The lower frame 28 is preferably secured to the lower end of the suction head and the upper frame is supported upon bolts 30 ad- 85 justably carried in brackets or arms 31 and having compression springs 32 surrounding the same between the frame and the bracket arms. These springs permit the raising and lowering of the hood so as to accommodate 90 itself to the inaccuracies in the road surface and also permit the raising of the suction head 23.

At the forward end of the vehicle, there is preferably provided a fender 33 which 95 is arranged diagonally across the vehicle so as to force large objects to one side of the same and prevent engagement thereof by the hood. Adjacent the rear of the vehicle immediately in front of the hood is a 100 scraper 34 normally raised from the ground by means of a spring 35 and actuated by a connecting rod 36 and lever 37 so as to be brought into engagement with the road surface for loosening the dirt thereon. The body 7 is preferably provided with an exhaust opening 38 which is controlled by a sliding screen 39 having an operating handle 40 and the hood is provided with a registering opening. The hood is preferably 110

supported upon suitable rollers 41, as shown. In order to raise the hood and the suction head from the ground, there is pivoted to the front of the vehicle adjacent the driver's seat a lever 42 connected to an arm 43 on the suction head by means of a cable 44 which passes over pulleys 45 mounted upon the top of the body 7.

It will be seen that the suction head is held adjacent the rear of the hood so that any dirt exhausting through the screen 39 and falling in the rear of the suction head will be thereby picked up again and carried into the dust chamber 9. The hood is of such size and material of such quality as to permit the exhaust from the blower to readily escape without placing any strain thereon and some air is filtered through the canvas fabric of the hood, as will be readily understood.

What is claimed is:—

1. In a street cleaner, a truck, a closed receptacle mounted thereon, a suction pump arranged to discharge in the receptacle, said receptacle having a screened exhaust opening, a suction head connected to the pump

and a hood surrounding the suction head and covering the exhaust opening, means for supporting the hood upon the ground, and means to resiliently hold the same in engagement with the ground.

2. In a street cleaner, a truck, a closed body mounted thereon and having an exhaust opening, a partition dividing the body into separate compartments, a suction pump arranged in one compartment, means for driving said suction pump, a suction head connected to the pump, a hood surrounding and connected to the suction head, means for supporting the hood upon the ground, means for resiliently holding the hood in engagement with the ground, and means for raising the head and hood against said holding means.

In testimony whereof we affix our signatures in presence of two witnesses.

THOMAS R. MURRAY.
JAMES P. MURRAY.
EDWARD S. NEILAN.
